UNITED STATES PATENT OFFICE.

WILLIAM DREW, OF PHILADELPHIA, PENNSYLVANIA.

FUSIBLE PLUG.

1,179,082.

Specification of Letters Patent. Patented Apr. 11, 1916.

Application filed September 15, 1914. Serial No. 861,768.

To all whom it may concern:

Be it known that I, WILLIAM DREW, a citizen of the United States, residing at Philadelphia, in the county of Philadelphia and State of Pennsylvania, have invented 5 certain new and useful Improvements in Fusible Plugs, of which the following is a specification.

My invention relates to improvements in 10 fusible plugs, the object of the invention being to provide a fusible plug which can be readily removed and replaced without disturbing the casing of the plug and which plug extends entirely through the casing 15 and follower, filling the same from the fire to the water side of the plug, so that there is no space to hold water.

A further object is to provide a fusible 20 plug widest at its center and tapering to both ends, so that both ends are of truncated conical form, one conical end fitting the conical bore of the casing, and the other conical end fitting the conical bore of the follower, so that when the latter is screwed 25 into place, the plug is securely held and made absolutely water tight.

With these and other objects in view, the invention consists in certain novel features of construction, and combinations and arrangements of parts as will be more fully 30 hereinafter described and pointed out in the claim.

In the accompanying drawings: Figure 1 is a view in longitudinal section illustrating 35 my improvements. Fig. 2 is an end view, and Fig. 3 is a perspective view of the fusible plug.

1 represents an externally screw-threaded casing which is screwed into an opening 2 40 in the boiler sheet 3 directly above the fire box. The casing 1 is provided in its end with an internally screw-threaded recess 4 to receive a screw-threaded follower 5, and said casing 1 is provided with an angular 45 enlargement 6, while the follower 5 is provided with an angular enlargement 7 to receive an ordinary wrench to facilitate the movements of the parts.

Casing 1 is provided with a tapering or 50 conical bore 8 extending from the inner end of the recess 4 where said bore is of greatest diameter to the end of the casing where the bore is of least diameter.

The follower 5 is provided with an internal truncated conical bore 9, largest in 55 diameter at the inner end of the follower,

and gradually decreasing in diameter to the outer end of the follower.

10 represents my improved fusible plug which is preferably of Banca tin, and which is of greatest diameter midway its ends, and tapers from the center to both ends. The plug 10 at one end, fits the bore 8 of casing 1, and at its other end fits the bore 9 of follower 5, so that when said follower is 60 screwed tightly into place, practically the entire surface of the plug will be frictionally engaged, one-half of the plug engaged by the casing, and the other half by the follower.

The plug is of a length to extend from the end of the casing to the end of the follower, and lies flush with the metal surfaces of the casing and follower. When it is desired to remove the plug, it is simply 70 necessary to remove the follower when the plug can be readily displaced from the casing and replaced by a new plug.

When the water falls below the proper level, the heat of the fire will rapidly fuse 80 the plug, and as the plug is tapering in form from the center to both ends, it will flow freely and entirely out of the casing and follower, and there will be a full and unobstructed passage for the water or steam.

85 My improved construction of plug is absolutely steam and water tight, and yet can be readily removed and replaced as may be desired.

Various slight changes might be made in 90 the general form and arrangement of parts described without departing from my invention, and hence I do not limit myself to the precise details set forth, but consider myself at liberty to make such changes and 95 alterations as fairly fall within the spirit and scope of the appended claim.

Having thus described my invention, what I claim as new and desire to secure 100 by Letters Patent is:

The combination with an externally screw-threaded casing having an internal screw-threaded recess in one end, and a conical tapering bore largest in diameter at the inner end of said recess and decreasing in 105 diameter to the end of the casing, of an externally screw-threaded follower adapted to screw into the recess in the casing and having a truncated conical tapering bore largest in diameter at the inner end of the follower, and decreasing in diameter to the outer end of the follower, and a plug of fusible ma- 110

terial largest in diameter at its center and tapering to both ends, the largest diameter of the plug located between the inner end of the follower and the inner end of the 5 recess, said plug fitting the bores of the casing and the follower and extending from the extreme end of the follower to the extreme end of the casing, substantially as described.

In testimony whereof I have signed my name to this specification in the presence of 10 two subscribing witnesses.

WILLIAM DREW.
